By John H. Redstone
Attorney in Fact.

UNITED STATES PATENT OFFICE.

GEORGE W. ARPER, OF OAKLAND, CALIFORNIA.

SIPHON.

SPECIFICATION forming part of Letters Patent No. 339,127, dated April 6, 1886.

Application filed April 17, 1885. Serial No. 162,601. (No model.)

To all whom it may concern:

Be it known that I, GEORGE W. ARPER, a citizen of the United States, residing at Oakland, in the county of Alameda, in the State 5 of California, have invented a new and useful Siphon, of which the following is a specification.

My invention relates to improvements in compound siphon and faucet, which will be 10 fully explained by reference to the accompanying drawing and the letters marked thereon.

Figure 1 is a side elevation showing the corner of a coal-oil can with the siphon inserted and a part of the can broken out to 15 show the lower end of the short or receiving arm of the siphon. It also shows the adjusting-brace, which holds the siphon firmly in position to be used as a faucet for drawing off the liquid from the can. Fig. 2 is a plan view 20 of the same shown in Fig. 1. Fig. 3 shows the adjusting-brace detached. Fig. 4 is a section showing the discharge or faucet end of the siphon. Fig. 5 is a side elevation showing the drip-cup to prevent the dropping from 25 the faucet.

The following is the construction of the same; I form the siphon A of gas-pipe or other suitable tubing. I cut the lower end of the siphon smoothly off, and cut a thread or 30 screw, B, upon the same to receive the valve-chamber C. The valve-chamber C has the ports D leading to the nozzle E. The packing F forms the valve to close and open the end of the siphon or discharge arm as the same is 35 screwed on or unscrewed. I form the packing or valve F of any suitable packing material to close the end of the pipe and form a tight joint.

The following is the operation of the same as 40 I apply it to the ordinary coal-oil can. I form an opening close to the corner of the same at the top and insert the siphon, as shown in Figs. 1 and 2, the siphon being filled as its nature requires, and the lower extremity of 45 the arm A' closed by closing the packing or valve F by the lever L. The bracket-brace J is then set against the corner of the can, and

the siphon-arm A' set in the notch N, where it is firmly held by the spring of the siphon, which presses it firmly in the notch N, as before shown. I then place the lamp or other vessel to be filled under the nozzle E, and unscrew the valve-chamber C by means of the lever L, thus withdrawing the packing or valve F from the end of the siphon-arm A', thus 50 allowing the liquid to flow freely through the ports D and nozzle E by the well-known siphon action. It is generally designed to insert the siphon so that the receiving or supply arm A reaches close to the bottom of the can; but it 55 may be adjusted by the leather or other suitable washer-rest H, shown in Figs. 1 and 2. This washer H is made to fit sufficiently tight to hold the weight of the siphon at any point where it may be shifted, although a set-screw or other well-known device may be employed to hold it in place when adjusted. As soon as 60 the vessel is filled the valve-chamber C and nozzle E are set up upon screw B and the valve F is brought tightly against the end of 65 the pipe A' and a perfectly tight joint formed. It will be seen that the brace J is only employed to hold the siphon in position and the arm A' out from the corner of the can and the arm A firmly in the inner corner of the same, 70 thus securing it firmly. The drip-cup K is designed to catch the drippings from the nozzle E and prevent the same from falling on the floor.

Having thus described my invention, what 75 I claim, and desire to secure by Letters Patent, is—

In siphons, the siphon described, comprising a can, a pipe, and adjusting-screw H, braces J, recessed to receive the corners of the can 80 and the pipes, a valve-chamber screwed on the lower end of the pipe and having ports D, the valve F, the arm L, attached to the valve-chamber, and the nozzle, substantially as set forth.

GEO. W. ARPER.
